SYLVESTER S. GREENE, OF HENRIETTA, NEW YORK.

Design No. 4,013, dated May 10, 1870.

DESIGN FOR FIRE-TONGS.

The Schedule referred to in these Letters Patent and making part of the same.

I, SYLVESTER S. GREENE, of Henrietta, in the county of Monroe and State of New York, have invented and produced a certain new and original Design for Fire-Tongs and Griddle-Holders, of which the following is a specification.

The nature of my design consists in the eccentric joint, the guards or rests for the hands, and in the foot of one of the clamp-bars, substantially as hereinafter shown and described.

In the accompanying drawings—

Figure 1 is a side view of a device representing my improved design, and

Figure 2 a flat view of one of the feet and a portion of the clamp-bar.

A A indicate the clamp-bars or legs of the tongs, which are curved substantially in the form represented. They may be made either of cast, malleable, or wrought iron.

The parts A A are hinged together at one end, forming the head or joint B. One side of this joint is formed with an eccentric bearing or stop, c, and the other side with a shoulder, d. In throwing the tongs open, the shoulder d strikes against the eccentric bearing c, so as to prevent them from opening too far.

If desired, the bars A, at a proper distance from the joint B, may be formed with guards or rests g g, which serve to protect the hands and prevent them from slipping.

The feet or bearings h h of the clamp bars A are flattened or widened as shown, and one of them is preferably provided with lateral wings or flanges i i. These wings provide a broad bearing, and prevent the clamp-bars from slipping by or crossing each other in case the joint B becomes loose. It also serves as a griddle-holder, when the said wings hold the griddle in a level position and prevent it from tipping or turning on the holder.

What I claim as new and original is—

The design for fire-tongs and griddle-holder herein shown and described, substantially as set forth.

In testimony whereof, I hereunto sign my name in the presence of two subscribing witnesses.

S. S. GREENE.
